UNITED STATES PATENT OFFICE.

DAVID BUTLER, OF MONTEZUMA, NEW YORK.

AUTOMOBILE RADIATOR.

Application filed April 27, 1927. Serial No. 187,003.

My invention relates to automobile radiators of the type employed in connection with water cooled engines.

It is the purpose of my invention to provide a construction which will prevent freezing of water within a radiator while the automobile is running, and which will constitute an effective and efficient means for rapidly thawing out the radiator in the event 10 freezing of water has developed in the radiator while the automobile is idle.

Furthermore, it is the purpose of my present invention to provide a construction which will not only accomplish the results 15 heretofore mentioned, but will also serve to materially reduce, if not entirely eliminate, deposit of vapor moisture upon the working parts beneath the hood of the automobile with resultant rusting of such parts.

20 With the foregoing and other purposes in view my invention consists in the arrangement and combination of parts to be herein-after more fully described and claimed.

In describing my invention in detail reference will be had to the accompanying drawing wherein like characters of reference denote corresponding parts in the different views, and in which

Figure 1 is a rear elevation of an automobile radiator embodying my invention, and

Figure 2, a section on the line 2—2 of Figure 1.

In the drawing A indicates generally an 35 automobile radiator of conventional construction which includes an upper header 10, a lower header 11, a removable cap 12, and a steam overflow pipe 13. As is usual the pipe 13 has the major portion of its length 40 located exteriorly of the radiator at the rear of the latter. The upper end portion of the pipe 13 enters the rear wall of the upper header and terminates within the usual header nipple 14 which receives the cap 12. Within the lower header 11 I provide a pipe 45 coil 15 both ends of which extend through the rear side wall of the header 11. One end of the coil 15 I connect to the lower end of the steam overflow pipe 13 by a suitable 50 union 16, while the other end thereof terminates in a downwardly directed portion 17.

In operation it will be apparent that with the engine running any accumulation of

steam in the upper header 10 will slightly raise the pressure in said header and such 55 steam will therefore be forced into and through the overflow pipe 13 and thence through the coil 15 from which latter the inherent heat of the steam will be radiated to raise the temperature of the water in the 60 lower header 11, at which latter point the temperature of the water in the standard radiators now in use is always lowest. It will also be noted that the radiation of heat by the coil 15 more completely condenses the 65 steam therein, so that the amount of moist vapor discharged from the end of the coil is materially reduced as is likewise the amount of moisture deposited on the working parts beneath the hood of the automobile 70 with appreciable diminution of rust on such parts.

Again, assuming that the water in the radiator becomes frozen while the automobile is idle. Upon operation of the engine 75 the water in the cylinder jackets will soon be converted into steam owing to the interruption of the circulation of the cooling system. The steam thus generated is discharged into the upper header 10 through 80 the usual connection between the latter and the engine. This steam will then pass through the pipe 13 into the coil 15 from which latter its heat will be radiated and effect thawing of the frozen water in an efficient manner and at the point in the radiator where the most complete freezing occurs. 85

I claim:

The combination with an automobile radiator including upper and lower radiators; of a steam overflow pipe extending continuously downward from the upper header and having its lower end disposed in the lower header, and a pipe coil in the lower header having one terminal secured to the 90 lower end of the steam overflow pipe and its other terminal directed downwardly through the bottom wall of the radiator, all portions of said coil between the terminals thereof being located in a horizontal plane 95 whereby the formation of a liquid seal within the coil by the condensation of vapor is prevented.

In testimony whereof I hereunto affix my signature.

DAVID BUTLER.
